MOVABLE LOUVER

Louis Cosowsky, Brooklyn, N. Y.

Application February 26, 1940, Serial No. 320,793

4 Claims. (Cl. 98—107)

This invention relates to new and useful improvements in a movable louver.

The invention particularly proposes to characterize the louver by a tubular body adapted to be engaged through a wall, and having outwardly extending flanges on its front and rear ends, and shutter plates mounted across the sides of said frame and operated in a particular manner.

More specifically, the invention contemplates mounting the shutter plates on a plurality of spaced parallel rods which are turnably mounted between opposite walls of the tubular frame, and it is proposed to provide the rods with crank portions on one of their ends disposed in a space between the tubular frame and an end wall mounted across the flanges of the tubular frame, and further proposed to provide certain mechanism for moving said crank portions in unison for opening and closing the shutter plates.

20 The invention contemplates the use of a bar connecting the cranks together to move in unison, and a novel arrangement for moving the bar to open and close the shutter plates.

Another object of the invention resides in characterizing the means mentioned in the previous paragraph by a pivotally mounted handle of limited amplitude associated with a link which is pivotally connected with the handle and pivotally connected with the bar and serves to transmit an oscillating motion to the bar when the handle is moved.

Still further it is proposed to provide a means for shifting the link along the handle to various positions to control the extent to which the shutter plates are opened.

For further comprehension of the invention, and of the objects and advantages thereof, reference will be had to the following description and accompanying drawing, and to the appended 40 claims in which the various novel features of the invention are more particularly set forth.

In the accompanying drawing forming a material part of this disclosure—

Fig. 1 is a perspective view of a movable louver constructed according to this invention.

Fig. 2 is a transverse vertical sectional view taken on the line 2—2 of Fig. 1.

Fig. 3 is a transverse vertical sectional view taken on the line 3—3 of Fig. 1.

Fig. 4 is a reduced elevational view looking in the direction of the line 4—4 of Fig. 3.

Fig. 5 is an enlarged horizontal sectional view taken on the line 5—5 of Fig. 4.

55 Fig. 6 is a fragmentary edge elevational view

similar to Fig. 3 but illustrating a modified form of the invention.

Fig. 7 is a fragmentary horizontal sectional view taken on the line 7—7 of Fig. 6.

Fig. 8 is a perspective view of the handle used in Figs. 6 and 7, illustrated per se.

The movable louver, according to this invention, includes a tubular frame 10 for engagement through a wall and having outwardly extending flanges 10^a and 10^b at its front and rear ends, 10 respectively. The tubular frame 10 has a shoulder portion 10^c near its rear end. The top wall 10^d of the frame tapers downwards from the front to the rear. The side walls 10^e and the bottom wall 10^f are straight from the front to the rear. 15 A screen 11 is mounted across the outside flange 10^b. This screen has edge portions 11^c bent over the edges of the flange 10^b.

End walls 12 are mounted across the edges of the flanges 10^a and 10^b. The flange 10^a has an inturned lip 10^{aa} to facilitate the supporting of these end walls. A plurality of spaced parallel rods 14 are turnably mounted between opposite side walls of the tubular frame 10. These rods 14 have crank portions 14^a on one of their ends. 20 These crank portions are disposed in the space between the side wall of the tubular frame 10 and the end walls 12. Shutter plates 15 are mounted upon the rods 14 and extend in length across the sides of the tubular frame 10. These shutter plates have curved top portions 15^a adapted to mate with the bottom edges of adjacent shutter plates in a manner to close the louver when the shutter plates are substantially in the vertical plane. The uppermost shutter plate 15 is 30 adapted to engage against the shoulder 10^c. The ends of each of the shutter plates 15 also engage against the shoulder 10^c, but more specifically, only against the shoulder portions 10^c at the sides of the frame 10. The dot and dash lines 35 in Fig. 2, indicate the open positions of the shutter plates 15.

A bar 17 connects the crank 14^a together to move in unison with each other. This is accomplished merely by forming openings 18 in the bar 45 17 through which the ends of the cranks 14^a engage. The bar 17 is vertically slidably guided by several straps 19 mounted upon the side wall of the tubular frame 10.

50 A pivotally mounted handle 20 of limited amplitude projects through an opening in the front flange 10^a. This handle has a double hook shaped front end 20^a adapted to be engaged by a conventional window opening pole in a manner so 55

that the louver may be opened or closed as hereinafter more fully described.

The handle 20 is pivotally supported by a pintle 21 mounted on the side wall of the tubular frame 10. The handle 20 is limited in amplitude by pins 22 and 23 which are mounted upon and project from the side wall of the tubular frame 10 and are located above and below the inner end of the handle 20. A link 24 is pivotally connected at one end with the handle 20 and extends downwards at a slight angle and is pivotally connected with the bar 17. This pivotal connection is accomplished by having the link 24 engage the uppermost crank 14a. The dot and dash lines 28, 17 and 14a in Fig. 3 represent the shifted positions of the corresponding full line parts which they assume when the louver is opened.

The operation of the device is as follows:

As illustrated by the full lines on the drawing, the louver is in its closed position. In order to open the louver it is required that a window pole or other implement be engaged against the bottom of the extended end of the handle 20, and then the handle is forced upwards. This indirectly forces the bar 17 downwards which indirectly turns the rods 14. The shutters 15 which are attached to the rods correspondingly turn and now the louver is opened. It may be closed by engaging a hook on the extended end of the handle 20 and pulling down to pull the handle 20 back to its original position.

In Figs. 6-8 inclusive a modified form of the invention has been disclosed which is very similar to the prior form, distinguishing merely in the fact that a means has been provided for shifting the link 24 along the handle 20' for varying the amplitude through which the shutter plates 15 are moved by operation of the handle 20. Specifically, this means includes a rod 26 which is rotatively mounted upon the handle 20'. This rod has a head 27 on its inner end rotatively engaging a socket 28 formed on the handle 20'. The handle 20' is provided with several stamped out strip portions 29 near its outer end which form bearings for the rod 26. A head 30 is mounted on the extended end of the rod by which the rod may be readily turned. A follower 31 is threadedly engaged on a section of the rod 26. The link 24 is pivotally connected with the follower 31 by a pintle 32. In other respects this form of the invention is similar to the previous form.

The operation of this form of the device is as follows:

The handle 20' may be rotated to move the follower 31 along the threaded portion of the rod 26. Since the top one of the shutter plates 15 is engaging the shoulder 10c and cannot move, the handle 20' will pivot a distance depending on the amount that the screw 26 is turned. Moreover, the follower 31 will assume a position spaced a greater distance from the pivot 21 of the handle 20'. The louver may be opened similar to the functioning previously described. The handle 20' is forced upwards. This moves the inner end of the handle downwards and the motion is transmitted by the link 24 to move the bar 17 downwards. However, since the follower 31 is at a greater distance from the pivot 21 it will move through a larger arcuate distance, and so move the bar 17 through a larger distance. This will control the extent to which the shutter plates 15 open when the handle 20' is moved to its fully opened position.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A movable louver, comprising a tubular frame, for engagement through a wall and having outwardly extending flanges on its front and rear ends, a screen mounted across the outside one of said flanges, end walls mounted across the edges of said flanges, a plurality of spaced parallel rods turnably mounted between opposite walls of said tubular frame and having crank portions on one of their ends disposed in the space between said tubular frame and one of said end walls, shutter plates mounted on said rods and extending across said tubular frame, a bar connecting said cranks together to move in unison, a pivotally mounted limited amplitude handle projecting from said front flange and having an inner end, a link pivotally connected with said handle and pivotally connected with said bar, and means for shifting said link along said handle to various positions, including a rod rotatively mounted on the handle and having a threaded section, a follower mounted on said threaded section, and said link being pivotally mounted on said follower.

2. A movable louver, comprising a tubular frame, for engagement through a wall and having outwardly extending flanges on its front and rear ends, a screen mounted across the outside one of said flanges, end walls mounted across the edges of said flanges, a plurality of spaced parallel rods turnably mounted between opposite walls of said tubular frame and having crank portions on one of their ends disposed in the space between said tubular frame and one of said end walls, shutter plates mounted on said rods and extending across said tubular frame, a bar connecting said cranks together to move in unison, a pivotally mounted limited amplitude handle projecting from said front flange and having an inner end, a link pivotally connected with said handle and pivotally connected with said bar, and means for shifting said link along said handle to various positions, including a rod rotatively mounted on the handle and having a threaded section, a follower mounted on said threaded section, and said link being pivotally mounted on said follower, and said rod being extended to the outer end of the handle and provided with a head by which it may be readily turned.

3. In a device of the class described, a frame, a plurality of spaced rods turnably mounted between opposite walls of said frame, crank portions formed on the ends of said rods, shutter plates mounted on said rods and extending across said frame, a bar connecting said cranks to move in unison, a pivotally mounted handle, a link having one end pivotally connected to said bar, a follower pivotally mounted on the free end of said link and slidably engaging a longitudinal slot in said handle, and means for holding said follower in various shifted positions along the length of said slot for changing the point of pivotal connection of said link with said handle to control the distance through which said shutter plates will move when said handle is pivoted.

4. In a device of the class described, a frame,

a plurality of spaced rods turnably mounted between opposite walls of said frame, crank portions formed on the ends of said rods, shutter plates mounted on said rods and extending across said frame, a bar connecting said cranks to move in unison, a pivotally mounted handle, a link having one end pivotally connected to said bar, a follower pivotally mounted on the free end of said link and slidably engaging a longitudinal slot in 5
10 said handle, and means for holding said follower

in various shifted positions along the length of said slot for changing the point of pivotal connection of said link with said handle to control the distance through which said shutter plates will move when said handle is pivoted, comprising a rod rotatively mounted on said handle and having a threaded section engaging through said follower for shifting said follower along the length of said slot as said rod is turned.
